SWEETENING HYDROCARBON DISTILLATES

Gert H. Weisemann, Hobart, Ind., assignor to
Standard Oil Company, Chicago, Ill., a corpora-
tion of Indiana

Application March 8, 1950, Serial No. 148,303

9 Claims. (Cl. 196—29)

1

This invention relates to the refining of hydrocarbon distillates, such as heavy naphtha, kerosene, heater oil and furnace oil, which are derived from the distillation of crude oil or from cracking processes, either thermal or catalytic. More particularly the invention relates to a method of treating such stocks with concentrated potassium hydroxide solutions in the presence of a copper catalyst to remove mercaptans therefrom.

It has heretofore been the practice to treat sour mercaptan-containing hydrocarbon distillates with alkaline solutions of various sorts to remove the mercaptans. Where low molecular weight mercaptans are involved as in the case of low-boiling distillates such as light naphthas, removal of mercaptans can be effected by simply washing with caustic alkali, e. g., caustic soda or caustic potash. For this purpose it is usually the practice to employ a caustic soda solution of about 10 to 20 per cent concentration. The caustic solution can be regenerated by steaming or air blowing to distil off the mercaptans or convert them to insoluble disulfides which can be separated from the caustic solution.

In the case of higher boiling stocks, particularly kerosene and heater oils, the removal of the mercaptans is much more difficult because of their increased oil solubility or higher oil-water partition coefficient due to their higher molecular weight. Numerous methods have been proposed and practiced for removing heavy mercaptans of the type found in these higher boiling distillates. Alkaline solutions containing organic solvents or so-called "solutizers" have been employed. Caustic-methanol solutions have a similar action. Chemical reagents which oxidize the mercaptans to disulfides in the presence of the oil have also been extensively employed. Among these are the familiar alkaline sodium plumbite or doctor solution, alkaline hypochlorite solutions, etc. Some attempts have been made to remove mercaptans from petroleum distillates by treating with anhydrous caustic in the form of a dry powder or in solution or suspension in an organic solvent such as methanol. When operating in this way, however, serious color formation has resulted especially where the treatment was conducted at elevated temperatures, for example 150° F. and upwards. It has been found that to prevent color formation under these conditions it has been necessary to carefully exclude oxygen or air.

An object of this invention is to remove mercaptans from sour hydrocarbon oils with a mini-

2

mum of color degradation. Another object is to speed up mercaptan removal by the use of a copper catalyst in conjunction with air and caustic. Still another object is to remove mercaptans from sour hydrocarbon distillates by the use of air and regenerated caustic in the presence of a copper catalyst. A particular object is to reduce the mercaptans in sour hydrocarbon distillates which boil above the gasoline range with a minimum of color degradation or formation of oil-soluble color bodies.

It has been discovered that mercaptans can be removed from sour hydrocarbon distillates, even in the heater oil distillate boiling range, i. e. 15 350–650° F., without serious color formation by 20 treating with a controlled amount of air or oxygen in the presence of an aqueous potassium hydroxide solution having a concentration in the range of about 50 to 60 per cent by weight at a temperature of about 80 to 125° F. (but high enough to prevent solidification of caustic), at atmospheric or superatmospheric pressure and in the presence of a particular type of copper catalyst. Under these conditions the mercaptans are converted to disulfides without the formation of objectionable color bodies. The oil refined in this manner has also been found to be satisfactory from the standpoint of its burning characteristics when employed in sleeve-type burners. The amount of oxygen employed either as air or commercial oxygen is preferably about 25 one and one-half to two and one-half times that theoretically required for converting the mercaptans present to disulfides.

It has been found that the treating reaction is greatly facilitated by the presence of a small amount of copper, e. g. about .004 to 0.1 per cent by weight based on the potassium hydroxide solution in the form of a catalytically active copper compound or copper complex such as colloidal copper oxide. This corresponds to about 0.01 to 40 0.3 per cent of copper chloride, CuCl₂.2H₂O. With some catalysts larger amounts of copper may be used, e. g. up to 0.5 per cent by weight based on KOH, but usually it is not necessary to exceed 0.1 per cent. It is preferred to add the copper in the form of an aqueous solution of a copper salt such as copper chloride, sulfate, nitrate or acetate. The copper salt solution may be added directly to the potassium hydroxide solution if the latter is hot enough to avoid formation of a black precipitate. When added in this way, for example to boiling potassium hydroxide solution, a blue complex forms which 45 appears to be a colloidal copper compound; in

this form and concentration the copper remains in active condition and does not precipitate from the potassium hydroxide treating reagent.

The copper catalyst can also be added to an intimate reaction mixture of KOH solution and oil, the oil in this case forming the continuous phase of an emulsion so that when the copper salt is introduced it is also dispersed and results in the formation of active catalyst instead of inactive black precipitate. When operating in this way the solution of KOH is mixed with the oil, for example in a continuous mixer, during or after which a solution of a water-soluble copper salt is introduced. The oil and treating agent is then passed to another mixer into which air or oxygen is introduced. If desired, however, air may be introduced into the oil and KOH before adding the copper catalyst, the air, oil, KOH and catalyst being all maintained in intimate contact until mercaptans are substantially eliminated.

While the above methods of adding the copper catalyst work very well when fresh caustic solution is used, the use of regenerated caustic solutions which contain material dissolved out of the sour hydrocarbon results in a very large increase in the amount of copper catalyst needed. The addition of the copper catalyst to the hot regenerated caustic results in the formation of a heavy precipitate and the blue color of the catalytically active caustic solution does not appear until all the "poison" has been reacted. These reactive materials are believed to be oxygenated hydrocarbons. The heavy precipitate must be removed or it clogs the lines and the meters used in the process. I have discovered that the addition of the copper catalyst, as a concentrated water solution, directly to the oil, so as to form a very fine dispersion, probably a water-in-oil emulsion, before the caustic solution is added eliminates this problem and also results in better finished oil color with less catalyst consumption than is obtainable with fresh caustic-catalyst solution addition.

The invention is illustrated by the drawings which form a part of this specification and in which:

Figure 1 is a schematic diagram of an apparatus suitable for carrying out the process, and

Figures 2 and 3 are graphs of data illustrating the results obtained in the process.

It has been found that the use of a copper catalyst results in a phenomenal increase in the mercaptan oxidation reaction rate with markedly improved Saybolt color as is shown by the following tabulated data. The aeration times to reach a mercaptan number of 5 and color of the finished oil were obtained using 1 volume per cent of 55% aqueous KOH, 4.85 cubic feet of air per hour to 500 cc. of oil and 0.1% by weight on caustic, of $\text{CuCl}_2 \cdot 2\text{H}_2\text{O}$ addition.

° F.	No Catalyst		Catalyst Added	
	Minutes	Color	Minutes	Color
80	Not Attainable		14	+10
90	150	24	9	+10
120	50	1 NPA	4	+10
150	15	2 NPA	2	+4

It has been found that the use of the copper catalyst tends to prevent color formation, apparently by directing the oxidation reaction toward the conversion of mercaptans to disulfides. The cause of color formation is not fully under-

stood but is thought to be due in part to the oxidation of phenolic substances contained in high sulfur oils. This effect is apparent from the data shown graphically in Figure 2 obtained by treating 500 cc. of a sour West Texas heater oil with 1% by volume of KOH solution at 120° F. and air at the rate of 4.85 cubic feet per hour. The upper curve shows rapid formation of color, i. e. decrease in Saybolt Universal color values as the mercaptan number of the oil is reduced when treated with air and regenerated 55 per cent KOH. The lower curve illustrates the improved results obtained with the same KOH solution containing 0.1 per cent by weight of $\text{CuCl}_2 \cdot 2\text{H}_2\text{O}$.

In the operation of my process, it is important to control the temperature within the range of about 80 to 125° F. if a product of satisfactory color is to be obtained. Higher temperatures have been found to increase color formation. The following data show the effect of temperature on the reaction, particularly with respect to mercaptan number and color. The treats were made by using straight-run West Texas heater oil having a +16 color and a mercaptan number of 65. The treating reagent was a 55 per cent aqueous KOH solution containing 0.1 per cent $\text{CuCl}_2 \cdot 2\text{H}_2\text{O}$, the ratio of solution to oil being 1 per cent by volume. The oil and solution were vigorously agitated in the presence of air. The following results were obtained:

Temp., ° F.	Mercaptan No.	Color, Saybolt	Time, Minutes
80	3.2	+9	15
100	3.8	+9	15
120	3.5	+9	5
150	0	-16	8
150 ¹	3	0	3

¹ Data interpolated.

The following data illustrate the effect of concentration of copper catalyst on the rate of mercaptan oxidation reactions and the color of the oil. The oil used in these experiments was a straight-run West Texas heater oil having a color of about 17 Saybolt Universal and a mercaptan number of 69. The treats were carried out at about 80° F. with air and 1% by volume of an aqueous KOH solution of 55% concentration. In the data which follow the copper catalyst is given as weight per cent of the caustic solution.

$\text{CuCl}_2 \cdot 2\text{H}_2\text{O}$	Contact Time, Minutes	Mercaptan Number	Color Saybolt Universal
0.3	6	13.1	+13
	8	10.6	12
	10	9.0	11
	15	6.4	8
0.2	5	13.8	12
	8	9.9	12
	10	7.4	12
	15	4.5	9
0.1	5	13.1	12
	8	10.3	12
	10	8.3	12
	15	3.2	9
0.05	8	17.3	12
	10	13.5	11
	15	10.3	9
	8	23.7	10
0.01	10	19.6	9
	15	13.1	7

It is to be noted that the maximum oxidation rate occurred with a copper concentration of about 0.1 to 0.2 per cent $\text{CuCl}_2 \cdot 2\text{H}_2\text{O}$. It is also to be noted that the oil obtained under these conditions showed an improved color.

5

It is desirable to separate the oil from the caustic solution after a contact time of about 25 to 40 minutes in order to avoid color formation and a contact time greater than one hour has been found to decrease the Saybolt color value from 16 to 5 or lower. Usually a contact time of 5 to 30 minutes is sufficient, depending largely on the temperature.

The ratio of caustic solution to oil may be varied over a range from 0.5 per cent by volume to 10 or 15 per cent by volume, although about 5 per cent by volume has been found to give best results in the case of heater oil from West Texas crude. When employing only 1 per cent KOH solution, the problem of separating the spent KOH solution from the oil is more difficult than when larger volumes of solution are used. The effect of coalescing the treated oil is particularly valuable in the case of low KOH-oil ratios as will be observed from the following table:

	Color-Saybolt	Universal
Untreated oil	17	
Settled to remove spent KOH solution	9	
Coalesced	13	
Coalesced and washed with water	16	

Attempts to use the cheaper caustic soda instead of KOH for sweetening fuel oil distillates were unsuccessful. In comparison with NaOH solution, KOH gave a faster reaction and a sweet product before color formation developed. The KOH solution also separates from the oil more readily whereas the NaOH becomes emulsified or dissolved in the heavy oil and is difficult to remove, even in the subsequent water washing operation.

Figure 3 illustrates the superior action of KOH in comparison with NaOH solutions. The aeration time for reduction in mercaptan number is considerably greater for NaOH solution of the same concentration. Thus the aeration time required to reduce the mercaptan number from 80 to 60 was approximately 48 minutes with 25 per cent NaOH and only 24 minutes with KOH solution of the same concentration.

Figure 3 also shows the effect of concentration on rate of mercaptan oxidation and it will be noted that there is a tendency for the oxidation to cease entirely or level off at a given mercaptan number depending on the concentration. Thus 40 per cent KOH leveled off at the mercaptan number of about 22, whereas 50 per cent KOH permitted the mercaptan number to be reduced to about 7. These data were obtained with 500 cc. samples of a West Texas heater oil having a mercaptan number of 80, contacted with air and 1 per cent by volume of the caustic solution containing 0.1 per cent $\text{CuCl}_2 \cdot 2\text{H}_2\text{O}$. The temperature of contacting was 85° F. and the rate of air input was 4.85 cubic feet per hour.

The odor of the oil treated by my KOH-air oxidation process has been found to be satisfactory for marketing requirements if the oxidation is carried to a point where the mercaptan number is below about 5. (The mercaptan number is the number of milligrams of mercaptan sulfur per 100 cc. of oil, usually determined by titration with a standardized copper solution.) By employing about 5 volume per cent of caustic solution (55% concentration and containing about .02 weight per cent of copper in the form of active colloidal copper complex but introduced as aqueous cop-

6

per sulfate) based on oil treated, mercaptan numbers have been reduced to about 1 or practically zero and treated products of good odor have been obtained with a Saybolt color of 15 to 17 and with good color stability and excellent burning qualities.

While the above data were taken from bench scale work using fresh caustic with the copper catalyst added to the caustic solution, pilot plant work using regenerated caustic shows the superiority of adding the copper catalyst directly to the sour oil before the introduction of the caustic solution. The following data were obtained on a West Texas heater oil of about 70 mercaptan number and about +16 Saybolt color. In all cases the treating reagent was a 55% aqueous KOH solution, about 5 parts of this solution was used per 100 parts of the sour oil; and all runs were made at about 90° F.

Copper Added to—	Wt. Percent Catalyst Added Based on Caustic		Product Mercaptan No.	Product Color Saybolt
	$\text{CuSO}_4 \cdot 5\text{H}_2\text{O}$	As Copper		
25				
Caustic	0.5	0.13	0.3	+4
Do	0.5	0.13	3.5	+8
Oil	0.2	0.05	2.2	+15
Do	0.2	0.05	0.3	+9
Do	0.1	0.03	0.5	+9
Do	0.1	0.03	0.3	+8
Do	0.05	0.01	0.5	+12

These data show that much less copper catalyst is needed when the catalyst is added to the oil to get a finished oil that is nearly sweet and at the same time is of better color by 4 or 5 points on the Saybolt scale. The data also show that the amount of copper as copper salt, specifically as copper sulfate, needed is within the range of from about 0.01 to about 0.05 based on the caustic solution. To these advantages, there must be added the advantage of much more accurate control of the copper catalyst addition since the amount of catalyst remaining in the caustic solution after all the reactive hydrocarbons have been precipitated is always somewhat doubtful.

Best results are obtained when the catalyst solution is injected into sour oil in such a manner that the solution is dispersed throughout the oil in very fine droplets. Preferably the dispersion should be so fine that a water-in-oil emulsion is formed. The dispersed copper compound apparently reacts with the KOH solution to form a catalytically active copper compound which is finely dispersed throughout the oil; this dispersion may be an explanation of the fact that less catalyst is needed when the copper solution is added to the oil than when it is added to fresh KOH solution.

A fuller understanding of the treating process will be obtained from Figure 1 wherein the principal reaction vessel is indicated by A and the used KOH reconcentrator by B. Coalescers C and D are provided for complete removal of caustic from the oil and E is a settler for removing wash water from the treated oil. Referring to Figure 1, the sour oil, which may be given a preliminary wash with an alkaline solution, such as sodium hydroxide or carbonate, to remove hydrogen sulfide if this is present in the oil, is introduced by line 5 and the temperature is adjusted by heater 6 to a satisfactory point, such as 90° F. After flowing through meter 7 the sour oil passes through line 8 to mixer 9 which is indicated to be of the orifice type. Air is introduced by line 10 and flows

through meter 11 to line 8 and thence to mixer 9. The copper catalyst, preferably $\text{CuSO}_4 \cdot 5\text{H}_2\text{O}$ or $\text{CuCl}_2 \cdot 2\text{H}_2\text{O}$, in an amount of about 0.1 weight per cent on the caustic solution, is introduced in the form of a concentrated water solution, such as 10%, by line 12 and pump 13 into line 8 where the solution is finely dispersed throughout the sour oil. An aqueous KOH solution of about 55% concentration is introduced by line 16 into line 8 and thence to mixer 9. The KOH solution, the 10 air and the sour oil-copper catalyst emulsion are thoroughly mixed in mixer 9, a suitable residence time being about 35 seconds.

The resulting mixture flows by line 17 to reactor A where partial separation of KOH solution takes place. Oil and unused air pass by line 18 to air separator 19 from which the air is discharged by line 20. It is preferred to maintain the reactor A under pressure, for example about 100 p. s. i. g., reducing the pressure by valve 21 to about 15 p. s. i. g. to facilitate separation of air in separator 19. The use of pressure with air increases the rate of oxidation, and pressures in the range of 25 to 200 p. s. i. g. are satisfactory. Where oxygen is used, superatmospheric pressure is not ordinarily required. From separator 19 the oil flows by line 22 to coalescer C which is packed with a fibrous or finely granular material such as glass wool, rock wool, sand, etc., providing an extensive surface for the removal of colloidally 30 suspended KOH solution from the oil. The coalescer may be a horizontal drum packed with glass wool, as indicated, connected with settling chamber 23, or it may be a packed vertical drum, preferably arranged for downflow of oil through 35 the packing with a separating chamber at the bottom. By effecting a more rapid and complete removal of KOH, the coalescer serves to arrest the development of color in the presence of the KOH solution.

From coalescer C the oil flows by line 24 to a second stage coalescer D. The residence time of the oil in the coalescers is suitably about 5 to 10 minutes. From coalescer D the oil flows by line 25 to water mixer 26, water being introduced into the oil stream by line 27. Mixer 26 of the orifice type is shown, although any suitable efficient mechanical mixer may be substituted therefor. The amount of water introduced may suitably be about 5 to 10 per cent of the volume of the oil. The water-oil mixture is conducted by line 28 to water settler E from which waste water is withdrawn by line 29. Washed oil flows by line 30 to water coalescer 31, the finished oil being discharged from the system by line 32. Waste water from the coalescer is discharged by line 33.

From reactor A, spent KOH is withdrawn by line 34 to settler 35 where potassium cresylates are allowed to collect as an upper layer. The separated KOH is withdrawn by line 36 and pump 37 and thence flows by line 38 to reconcentrator B where it is heated by submerged steam coil 39 to drive off water which tends to accumulate in the system, particularly as a by-product of the sweetening reaction. Water eliminated as vapor is passed by line 40 to condenser 41 and is discharged from the system by line 42. The reconcentrated KOH flows by line 43 to cooler 44 and thence by line 45 to KOH solution filters 46 which remove potassium carbonate and any other insoluble products which may collect in the reagent. The KOH solution then flows by line 47 and pump 48 back to mixer 9 by line 16. Makeup KOH is supplied to the system from time to time by line 49 as needed. If desired, concentrator B may be

operated under reduced pressure, e. g. 5 p. s. i. a. and consequently the temperature can be held below about 280° F. thereby largely avoiding decomposition of mercaptides to K_2S which is undesirable because it separates and clogs the system. Such decomposition also represents a loss of KOH.

From the coalescers C and D, separated KOH solution is conducted by line 50 to separator 35. The cresylate layer from separator 35 is conducted by line 51 to separator 52 which may be a storage tank providing an extended time for settling out aqueous caustic. It has been found that the small amount of caustic insoluble copper compounds formed by reaction between the copper catalyst and reactive hydrocarbons is preferentially soluble in the cresylates and passes out of the system with the cresylate layer from separator 35; this fact eliminates the need for special measures to prevent clogging of lines and meters. The recovered KOH is conducted periodically by line 53 to the KOH line 36. If desired separator 52 can be provided with suitable means for heating the cresylates and thereby facilitating the separation of the KOH. The settled potassium cresylates are discharged from the system by line 54.

The finished oil contains a trace of copper but not more than about 1 part per million. The effect of this minute amount of copper on the color stability of the oil can be readily offset by the addition of a small amount of metal deactivator, e. g. 0.001 to 0.01% of N,N'-disalicylidine-1,2-diaminopropane.

While a particular system for using the invention has been described in considerable detail, many modifications and alternative procedures and conditions will be apparent from the above description to those skilled in the art. The amounts of catalyst specified in the accompanying claims refer to copper in the form of an active compound or complex believed to be colloidal oxide; such catalyst is preferably prepared as herein described using, for example, copper sulfate which has been found to give outstandingly good results.

I claim:

1. The process of removing mercaptans from sour hydrocarbon distillate which is higher boiling than gasoline without formation of excessive color therein, which comprises dispersing a copper catalyst in the distillate, intimately contacting said catalyst-containing distillate with about 1 to 15 per cent by volume of an aqueous solution of KOH having a concentration of about 50 to 60 per cent, said copper catalyst, which ranges from about 0.004 to 0.1 per cent by weight of copper based on the caustic solution, forming a catalytically active copper compound when contacted with the caustic solution, introducing a gas containing an amount of free oxygen about stoichiometrically equivalent to the amount of mercaptans present in said distillate into the mixture of catalyst-containing distillate and KOH, maintaining the temperature of contacting at about 80 to 125° F. until a substantial reduction in mercaptan content has been obtained and separating spent KOH solution and associated reaction products from the treated oil.

2. The process of sweetening a sour hydrocarbon distillate which is higher boiling than gasoline without formation of excessive color therein which comprises dispersing a copper compound in the distillate which will range from about 0.004 to 0.1 per cent by weight of copper on the caustic solution hereinafter described in the form

of a catalytically active copper compound, intimately contacting said catalyst-containing distillate with about 5 to 10 per cent by volume of an aqueous solution of KOH having a concentration of about 50 to 60 per cent, introducing into the reaction mixture air containing an amount of oxygen stoichiometrically equivalent to about one and one-half to two and one-half times the amount of mercaptans present in said distillate, maintaining said reaction mixture highly agitated and at a temperature of about 80 to 125° F. until the mercaptan number of said distillate is reduced below about 5, then separating spent KOH solution and associated reaction products from the treated oil.

3. The process of claim 2 wherein the time of contact between said distillate and said KOH solution is about 5 to 60 minutes.

4. The process of treating a sour virgin heater oil distillate containing a large amount of mercaptan sulfur, without materially impairing the color and color stability thereof, which process comprises dispersing a concentrated aqueous solution of copper sulfate, which solution contains between about 0.01 and 0.05 weight percent of copper based on aqueous KOH solution used in the process in the distillate, intimately contacting said copper sulfate-containing distillate with about 5 per cent by volume of a concentrated potassium hydroxide solution of about 50 to 60 per cent concentration, said copper compound forming with the potassium hydroxide solution a copper catalyst which is active as an oxidation catalyst, and with added free oxygen in an amount stoichiometrically equivalent to about one and one-half to two and one-half times the amount of mercaptans present in said distillate, continuing said contacting at a temperature in the range of about 80 to 125° F. under a pressure in the

range of atmospheric to 200 pounds per square inch for between about 5 and 30 minutes, then separating spent potassium hydroxide solution with reaction products contained therein from the treated oil, separating potassium cresylates from the withdrawn solution, then subjecting the solution to distillation at low pressure and at a temperature not exceeding about 300° F. for removing water therefrom, and returning the concentrated caustic solution for contacting with additional amounts of said distillate.

5. The process of claim 1 wherein said distillate is a sour virgin heater oil distillate.

15 6. The process of claim 1 wherein said copper catalyst is selected from the group consisting of copper chloride, copper sulfate, copper nitrate and copper acetate.

7. The process of claim 2 wherein said copper compound is selected from the group consisting of copper chloride, copper sulfate, copper nitrate and copper acetate.

20 8. The process of claim 4 wherein said copper compound is selected from the group consisting of copper chloride, copper sulfate, copper nitrate and copper acetate.

25 9. The process of claim 4 wherein said potassium hydroxide solution is a substantially saturated aqueous potassium hydroxide solution.
